Inventor:
James Johanson

UNITED STATES PATENT OFFICE.

JAMES JOHANESON, OF BELOIT, WISCONSIN.

SULKY-CULTIVATOR.

SPECIFICATION forming part of Letters Patent No. 242,134, dated May 31, 1881.

Application filed March 9, 1881. (Model.)

To all whom it may concern:

Be it known that I, JAMES JOHANESON, a citizen of the United States, residing at the city of Beloit, Rock county, and State of Wisconsin, have invented a certain new and useful Improvement in Sulky-Cultivators, of which the following is a specification.

My invention relates to improvements in sulky-cultivators; and the object of my improvement is to simplify the construction of the mechanism provided for operating and for better controlling the operation of the machine while doing field-work, a compound and combined device being provided for that purpose, whereby, also, the operator has more convenient, easy, and perfect control of the drag-bars carrying the cultivator-plows and appurtenant mechanism, and also largely cheapening the manufacture of cultivators containing my newly-invented improvement therein. I attain these objects by the mechanism illustrated in the accompanying drawings, in which—

Figure 1 is a perspective view of so much of an entire machine as is necessary for illustrating and showing the proper relation to and connection of my improvement therewith; and Fig. 2 is a detached view of a section of one of the vertical standards supporting the drag-bars, having universal ball-joints near the foot of each.

Similar letters refer to similar parts throughout the several views.

The forked tongue A, transverse bars B C, angular brace b, and ratchet R show the ordinary parts of the frame-work of a sulky-cultivator, exclusive of the appurtenant parts herein-after described, which contain my invention and constitute my improvement therein.

Letter E represents a vertical metal standard, its upper end bolted to the frame A, its foot being supported by the brace b, and provided near the lower end with a ball made solid thereon, (shown at Fig. 2,) which, in connection with the eye-socket i of the part D, constitutes a universal joint, upon which the drag-bar H oscillates.

K is a vertical lever-bar, pivoted to the frame A at i i, having a side lever, x, rigidly joined thereto, and oscillating laterally therewith upon the pivot at i i. The foot of the vertical lever-bar K is provided with a universal ball-

joint similar to that upon the standard E hereinabove described, which together constitute a compound leverage and a compound ball-joint device, whereby the drag-bars H are raised and lowered by means of actuating the hand-lever L and foot-levers g, (shown at Fig. 1,) but the arrangement and functions of which are hereinafter next particularly set forth. The front end of the foot-levers g is pivoted to the frame A at P, and is connected by a chain, x², at a suitable point for leverage, to the side lever, x.

The hand-lever L is pivoted to the vertical lever K at m, the side lever, x, forming a fulcrum for the lever L, which also is provided on its inside with a suitable pawl for engaging with the ratchet R, for holding it in the proper position.

Now, it will be seen and plainly understood that by depressing either the hand or foot levers the cultivator-plows upon the drag-bars will run at any desired depth, or may be raised entirely out of the ground by the operator from his seat upon the machine, and of course the drag-bars and plows will be lowered to the ground by their own gravity when pressure is removed from the levers.

The drag-bars will, as usual, be suitably connected at their rear ends, and will be properly swayed and guided laterally by the feet of the operator when at work, and will also be provided with necessary appurtenant usual devices to prevent injury to the growing corn.

The device D is made of metal, in two parts, secured together by a suitable screw or bolt, and bolted to the fore end of the drag-bars H, as shown.

It will be seen that by means of my improvement the drag-bars may be controlled wholly by the feet of the operator, or by the hands and feet alternately, as most convenient and easy, as preferred; and it will also be seen that by means of my improvement much of the usual complicated mechanism employed to operate the cultivator is rendered unnecessary and has been dispensed with; that the construction and arrangement of the operating mechanism are much cheapened and simplified, which is a cardinal principle lying at the very foundation of all branches of manufacture, and which, in general, is believed to be a very im-

portant improvement in this class of machines, and is the chief merit claimed for my invention.

My improvement herein consists, chiefly, in the peculiar construction and arrangement of the vertical metal standard E with the ball-joint thereon, as shown, the device D, the vertical lever K, side lever, x, with ball-joint, as shown, foot-levers g, chain-coupling x², as shown, and hand-lever L, all as shown and described.

It will be observed that only one side of the machine is illustrated and shown in the drawings.

I am aware that prior to my invention sulky-cultivators have been constructed and provided with hand-levers connected with other mechanism for operating the cultivating devices. I

therefore do not claim such construction, broadly; but

What I do claim as my invention, and desire to secure by Letters Patent, is—

The standard E, with ball-joint thereon, as shown, the device D and vertical lever K, with ball-joint, as shown, the side lever, x, coupling-chain x², the foot-lever g, and hand-lever L, whereby the cultivators are manipulated by the hands or feet of the operator from his seat upon the machine, substantially as and for the purpose herein particularly described and shown.

JAMES JOHANESON.
